UNITED STATES PATENT OFFICE.

JOHN C. BOGLE, OF CHICAGO, ILLINOIS, ASSIGNOR TO COOK ELECTRIC COMPANY, OF CHICAGO, ILLINOIS, A CORPORATION OF ILLINOIS.

RENEWABLE ELECTRIC FUSE.

Application filed December 1, 1922. Serial No. 604,159.

My invention relates to electric fuses and it has special reference to fuses that are known as enclosed renewable fuses.

More particularly my invention relates to an improved electric fuse provided with an insulating chamber having conducting terminals at its ends and a novel type of fuse link extending through the insulating chamber and contacting at each end with the terminals. I have shown the terminals to be of a type suitable for clamping the ends of the fuse link in place and also adapted in turn to be clamped by the usual type of fuse clips.

An object of my invention is to provide a fuse link for the above type of fuse which can be readily inserted in place and yet which does not require the use of washers for retaining its ends in contact with the fuse terminals.

A further object of my invention is to provide a device of the type indicated above, which is simple in construction, easily assembled, and dependable in operation.

Further objects of my invention will appear upon reference to the following specification and accompanying drawing, in which—

Figure 1 is a view in section of an enclosed renewable fuse structure constructed in accordance with my invention and shown in a partially assembled condition;

Fig. 2 is a view similar to Fig. 1, but showing the fuse fully assembled;

Fig. 3 is a detail view showing the fuse link; and,

Fig. 4 is a detail perspective view showing a ferrule member.

Referring to Fig. 1, a container 1 formed of insulating material is shown enclosing a special type of link 2. The container 1 is provided at each end with ferrules 3 and 4, which are in turn provided with threaded portions 5 and 6 for engaging cap members 7 and 8, respectively.

The particular type of cap members 7 and 8 shown, form no part of my present invention and they are similar in construction to those shown and described in my copending application, Serial No. 385,427, filed June 1, 1920, which has matured into Patent No. 1,443,865, granted January 30th, 1922. The cap members 7 and 8 are provided with centrally positioned tortuous passages 9 and 10

respectively, for the escape of gases formed when the fuse link is burned out.

The fuse link 2 comprises a centrally positioned fusible element 11, which may be formed of a ribbon of easily fusible metal, such as zinc, and of a cross section depending upon the current to be carried by the fuse. The fusible element 11 is attached at each end to supporting and connecting terminals 12 and 13, which serve to support the fusible element 11 rigidly in its proper central location and also serve to connect the fusible element in circuit without interposing any unnecessary resistance.

The connecting terminals 12 and 13 are provided with enlarged ends shaped in the form of flat washer portions 14 and 15 respectively. However, the end portion 14 is preferably initially formed in the distorted shape shown in Fig. 1 in order that it may be readily inserted through the shell 1 and the ferrules 3 and 4, when assembling the device or when renewing the fusible element. The washer portions 14 and 15 may be provided with the centrally located openings 16 and 17 respectively, coaxial with passages 9 and 10 in cap members 7 and 8. The ferrules 3 and 4 may be provided respectively with inturned flanges or rims 18 and 19 against which the faces of washers 14 and 15 may be clamped. If desired, the inner surfaces of the washers 14 and 15 may be slightly roughened as at 20 in Fig. 3, and also the outer surfaces of flanges 18 and 19 may be roughened as at 21 in Fig. 4. These roughened areas will serve to prevent relative turning movement of the link terminals and ferrules when the device is being assembled.

In the assembly of the device, the fuse link member 2 is placed in the container 1 by first inserting the washer portion 14, when in its distorted form. The washer portion 15 is then brought up against the flange 19 of ferrule 4 and securely clamped in place by the cap member 8. The washer portion 14 being formed of comparatively flexible material, may then be easily bent to a flattened shape approximating that shown in Fig. 3. The cap member 7 may then be screwed in place and will force the portion 14 into its fully flattened shape shown in Fig. 3.

When the fuse is fully assembled, it will be noted that the washer portions 14 and 15 will have a large surface area in contact with

the flanges 18 and 19 and with cap members 7 and 8, and that the use of the usual washers at this point will be thus rendered unnecessary. The elimination of the washers not only results in a more simple construction, but provides a construction which can be much more quickly assembled in case of an emergency.

The two ferrules 3 and 4 as shown are constructed alike and hence the link 2 may be inserted from either end and the link ends may be interchangeably associated with either of the fuse ends. Such construction avoids the necessity of examining the shell ends when it is desired to assemble the device quickly.

While I have shown and described but one embodiment of my invention, it is to be understood that many modifications may be made therein without departing from the scope of the appended claims and I desire to have only such limitations imposed upon my invention as are necessitated by the prior art or set forth in the appended claims.

Having thus described my invention, what I claim as new and desire to secure by Letters Patent in the United States, is:

1. A fuse comprising a shell member, a fuse link constituting a fusible element having an enlarged end portion of flexible sheet material initially curved in shape to reduce its dimensions while being installed in operative position in said shell member but capable of being expanded after installation to engage the outer periphery of said shell member thereby serving as a washer member upon being flattened.

2. A fuse comprising a shell member, a fuse link constituting a fusible element, and a terminal member for said fusible element, said terminal member having an end portion of flexible sheet material curved in a shape permitting its free insertion through said fuse shell member having an opening of a certain diameter, said end portion being of sufficient area upon being flattened subsequent to installation in said shell member to substantially cover an opening of such diameter.

3. An enclosed type fuse comprising a shell member, and a fuse link in said shell member, said fuse link having an enlarged flexible end portion of sheet material initially formed in a shape to pass freely through said shell and forming when flattened a washer for covering and contacting with the end of said shell member.

4. An enclosed type fuse comprising a shell member, an end cap on one end of said shell member, and a fuse link in said shell member, said fuse link having a flexible end portion of sheet material initially formed

in a shape to pass freely through said shell and forming normally, when flattened and expanded, a washer exceeding the size of the opening in said shell member and being clamped beneath said end cap, which washer serves as a closure for the end of said shell.

5. An enclosed type fuse comprising a shell member, an end cap on one end of said shell member, and a fuse link in said shell member, said fuse link having a flexible end portion initially formed in a shape to pass freely through said shell and forming normally, when flattened, a washer clamped beneath said end cap, said washer and said end cap being formed with coaxial passages for venting said shell member.

6. An enclosed type fuse comprising a shell member, ferrules at the ends of said shell member, end caps engaging said ferrules, and a fuse link in said shell member, said fuse link having an enlarged flexible end portion initially formed in a shape to pass freely through said shell and forming normally, when flattened and expanded, a washer exceeding the size of the opening in said shell member and being clamped between said ferrules and said end caps.

7. An enclosed type fuse comprising a shell member, a ferrule at the end of said shell member, a cap member engaging said ferrule, and a fuse link extending through said shell member, said ferrule having an opening for insertion of said fuse link and said fuse link being provided with an enlarged end forming a washer covering said opening and clamped between said cap and said ferrule.

8. An enclosed type fuse comprising a shell member a ferrule at an end of said shell member and a fuse link in said shell member, said fuse link having an enlarged flexible end portion initially formed in a shape to pass freely through said shell and said ferrule and forming when flattened a washer for covering and contacting with a rim of said ferrule.

9. An enclosed type fuse comprising a shell member, a ferrule at an end of said shell member, a fuse link in said shell member, said fuse link having an enlarged flexible end portion initially formed in a shape to pass freely through said shell and said ferrule and forming when flattened a washer for covering and contacting with a rim of said ferrule and coacting means on said washer and said ferrule for preventing relative turning movement therebetween.

In witness whereof, I have hereunto subscribed my name.

JOHN C. BOGLE.
